UNITED STATES PATENT OFFICE.

WILLARD A. ORMSBEE, OF TAUNTON, MASSACHUSETTS, ASSIGNOR TO TAUNTON PEARL WORKS, INC., OF TAUNTON, MASSACHUSETTS, A CORPORATION OF MAINE.

DESIGN FOR A CUFF LINK.

Application filed December 17, 1924. Serial No. 11,719. Term of patent 3½ years.

To all whom it may concern:

Be it known that I, WILLARD A. ORMSBEE, a citizen of the United States of America, residing at Taunton, county of Bristol, State of Massachusetts, have invented a new, original, and ornamental Design for a Cuff Link, of which the following is a specification, reference being had to the accompanying drawing, forming a part thereof.

I claim:

The ornamental design for a cuff link, as shown.

WILLARD A. ORMSBEE.
